Abraham Kaufman
Aaron L. Applebaum

UNITED STATES PATENT OFFICE

ABRAHAM KAUFMAN, OF NEW YORK, N. Y.

DISPLAY STAND

Application filed December 5, 1928. Serial No. 323,833.

This invention relates to display stands or supports for merchandise and the like having for its primary object to provide an adjustable stand, the height of which may be regulated and affording means for attaching or suspending the articles to be displayed.

One of the objects of my invention is to provide a display stand or support constructed and arranged to permit articles to be attached thereto at different positions without interference, one with the other, and at different heights so that the said articles or merchandise may be observed from any one of four sides.

More specifically my invention relates to a display stand or support having a base and a series of frames on which the merchandise is displayed including means for adjustably spacing the frames whereby the stand or support may be utilized in a store window, show case or on a display counter.

A further specific object of my invention is to provide a display stand or support for merchandise having a series of frames connected to a lazy tong extension, the height of which may be adjusted to accommodate the particular location or use to which the stand or support is to be employed.

To enable others skilled in the art to more fully comprehend the underlying features of my invention, reference is had to the accompanying drawing forming a part of this specification in which

Fig. 1 is a front view, partly in section showing my invention.

Fig. 2 is a top plan showing the frames.

Fig. 3 is a front view showing the stand in a second position.

Fig. 4 is a section taken on the line 4-4 of Fig. 1.

Fig. 5 is a section taken on the line 5-5 of Fig. 1.

Referring now to the drawings, 5 designates the feet or legs of a conventional type of solid base or support having a top shoulder 6 and a vertical central bore or opening entirely or partially through the said base to receive a post 7 preferably formed integral with a flanged plate 8. The post is loosely positioned in the bore or opening of the base

so that the super-structure of the stand or support may be rotated to any desired position.

Attached to the said plate 8 is a lazy tong construction, certain of the links 9, 10 being pivoted as at 11 to the plate and the longer links 12, 13 having pins or studs slideable in horizontal slots 14, 15 of said plate which limit the movement of the lazy tong construction in the extended position as shown by Fig. 1 and the folded or collapsed condition as shown by Fig. 3. The lazy tong construction is of considerable height so that the device may be adjusted to accommodate the particular position or use to which it is to be employed. A stud and wing nut 16 passing through certain of the links 17, 18 substantially intermediate the top and bottom lazy tong construction affords means for locking the same in any of its adjusted positions.

The lazy tongs also carry a plurality of superposed frames which may be square, rectangular, circular or any other desired shape. In the preferred form shown, the bottom square shaped frame 19 is provided with a transverse cross bar or rod 20, the ends 21 of which may be riveted or otherwise permanently fastened to the sides of the frame. The cross bar or rod is also provided with transverse slots 22 for the pivots or pins connecting certain of the links of the lazy tong construction. The intermediate rectangular frame 23 is provided with a similar, slotted transverse cross bar or rod and preferably slightly smaller in dimensions than the lower frame.

The top frame 24 is in turn slightly smaller than the intermediate frame 23 and the transverse cross rod or bar 25 is provided with slots 26 for receiving the pivots 27 of the links 28, 29 and the interconnected links 30, 31. In order to permit the lazy tong construction to be extended from the position shown by Fig. 3 to that of Fig. 1 for instance or vice versa, a flat handle grip 32 is attached to the cross bar or rod of the top frame, which grip may also be employed to attach or support an article to be displayed. As a convenient means of attaching an

article to the frames, the metal or material comprising said frames is struck out as at 33 to provide hooks to which are connected the ends of an expansible spring. 5 While I have shown a single spring 34 attached in the above manner to each of the sides of the respective frames, it will be understood that this construction may be duplicated where it is desired to provide a plurality of similar springs for the same purpose. Furthermore, it will also be understood that the shape of the frames may also be varied so as to provide a combination of rectangular, square, octagonal, circular or other 10 15 20 25 30 35 40 45 50 55 60 65 70 75 80 85 90 95 100 105 110 115 120 125 130

handle connected to the cross bar of the top frame and springs connected to the sides of each of the frames for supporting a plurality of objects or merchandise for display.

In testimony whereof I affix my signature. 70
ABRAHAM KAUFMAN.

While I have shown and described my invention with some degree of particularity, it 25 will be realized that other modifications and changes may be resorted to under special conditions. I therefore do not wish to be limited and restricted to the exact details shown and described but reserve the right to make such 30 35 40 45 50 55 60 65 70 75 80 85 90 95 100 105 110 115 120 125 130

Having shown and described my invention, what I claim as new and desire to secure by 35 Letters Patent is:—

1. A support or stand comprising a base, a plate having a post carried by said support, a lazy tong structure connected to the plate, a series of superposed frames fastened to the 40 45 50 55 60 65 70 75 80 85 90 95 100 105 110 115 120 125 130

lazy tong structure, said frames having means for attaching a plurality of objects or merchandise for display.

2. A support or stand comprising a base, a slotted plate having a post carried by said support, a lazy tong structure pivoted to the plate, a series of superposed frames attached in spaced relation to the lazy tong structure, means for locking said structure in an adjusted position and means attached to said 50 55 60 65 70 75 80 85 90 95 100 105 110 115 120 125 130

frames for supporting a plurality of objects or merchandise for display.

3. A support or stand comprising a base, a slotted plate having a post rotatably supported by said base, a lazy tong structure pivoted 55 60 65 70 75 80 85 90 95 100 105 110 115 120 125 130

to the plate, a series of superposed frames each having a slotted cross bar attached to said lazy tong structure, and resilient means carried by said frames for supporting a plurality of objects or merchandise for display.

4. A support or stand comprising a base, a slotted plate having a post rotatably supported by said base, a lazy tong structure pivoted to the plate, a series of frames each having a slotted cross bar attached in vertical spaced relation to said lazy tong structure, a
